UNITED STATES PATENT OFFICE.

JOHN P. SWIFT, OF PAWTUCKET, RHODE ISLAND, ASSIGNOR TO SAMUEL M. CONANT, OF CENTRAL FALLS, RHODE ISLAND.

PASSENGER-SUPPORTING STRAP.

SPECIFICATION forming part of Letters Patent No. 729,696, dated June 2, 1903.

Application filed March 26, 1903. Serial No. 149,606. (No model.)

To all whom it may concern:

Be it known that I, JOHN P. SWIFT, a citizen of the United States of America, and a resident of Pawtucket, Rhode Island, have invented certain new and useful Improvements in Passenger-Supporting Straps, of which the following is a specification.

My invention relates to improvements in passenger-supporting straps for electric cars and other vehicles; and the purpose of my invention is to provide a strap adapted to the use of persons of different heights without adjustment or change of the strap itself and which at the same time can be readily removed from the supporting-bar on which it is hung. I accomplish this purpose by the device shown in the accompanying drawings, in which—

Figure 1 is a perspective view of a portion of the supporting-bar from which the strap is suspended and the strap itself with its attachments; Figs. 2 and 3, the details of the strap, showing the method of removing the same from its supporting-bar.

The same parts are designated by the same letters throughout the several views.

In Fig. 1, B is the supporting-bar, attached to the roof or side of the car in the usual manner. A is the strap, having loops at a a^2 for the admission of the hand of the passenger, as shown. c is a wire clip inclosing the strap, as shown. b b^2 are checks or stops fixed to the fabric of the strap itself by means of the rivets b' b' . The loops a a^2 are formed by turning up the extremities of the strap and sewing the same, as at a' a' , although the ends may also be secured by any other suitable means. The stops b b^2 admit of the loops a a^2 being adjusted so as to accommodate persons of different heights, and this result is accomplished by the respective location of the stops b b^2 with reference to the loops a a^2 . If the two stops b b^2 are equally distant from their respective loops a a^2 , then

said loops a a^2 would by the weight of a passenger stop at an equal distance from the rod B; but by placing one stop b^2 in close proximity to the loop a^2 and the other stop b several inches away from its loop a then the loop a may be drawn down a considerable way farther than the loop a^2 , thus accommodating

a passenger of shorter stature. The two loops are limited in their reach by the stops b b^2 bringing up against the clip c, the fit of this clip being such that the strap A slides easily through it.

The strap A may be readily removed from the supporting-bar B, as shown in Figs. 2 and 3. The removal is accomplished as follows: The strap A is twisted over upon itself, so that the stop b is in approximately a vertical position, or at right angles to the clip c, as shown in Fig. 2. The opening through the clip c is such as to allow the stop b to pass through it when in the position shown in Figs. 2 and 3, the dotted lines in Fig. 2 showing the stop b after insertion into the clip. After b is once inserted into the clip c the strap is easily removed by pulling upward the member of the strap having the stop thereon, the loops a and a^2 being capable of passing easily through the clip c, as shown in Fig. 3.

My device may be made of leather or any other flexible and strong material; but I prefer to construct the same of cotton webbing, so that it may be readily removed and cleansed, thus providing a more sanitary arrangement than is found in the ordinary leather passenger-strap.

Any desired adjustment may be obtained by my device by shifting the respective locations of the stops b and b^2 with reference to their adjacent loops a and a^2 .

Any equivalent device—such as a handle, a ring, or the like—may be substituted for the loops a a^2 or the loops may be wholly omitted without changing my invention.

Having now described my invention, what I claim, and desire to secure by Letters Patent, is—

1. In a passenger-supporting strap the combination of a supporting-bar; a strap encircling the same; a clip loosely encircling both members of said strap immediately below said rod, and stops fixed one upon each member of said strap below said clip and at unequal distances from the ends of said straps, substantially as described for the purpose specified.

2. A passenger-supporting strap consisting of a supporting-bar in combination with a strap encircling the same, said strap having

a loop at each end thereof; a clip loosely en-
clasping both members of said strap immedi-
ately below said rod, and stops fixed one upon
each member of said strap below said clip and
5 at unequal distances from said loops, sub-
stantially as described for the purpose speci-
fied.

3. In a passenger-supporting strap the com-
bination of a supporting-bar; a strap encir-
10 cling the same; a clip loosely enclasping both
members of said strap; and stops fixed one on
each member of said strap below said clips

and at unequal distances from the ends of said
strap; said strap being removable from the
supporting-bar by passing either end thereof 15
with its stop through said clip, substantially
as set forth.

Signed at Pawtucket this 21st day of March,
1903.

JOHN P. SWIFT.
